UNITED STATES PATENT OFFICE

145,342

DESIGN FOR A BABY RATTLE

Irving Tucker, White Plains, N. Y.

Application September 17, 1945, Serial No. 122,151

Term of patent 3½ years

(Cl. D34—15)

To all whom it may concern:

Be it known that I, Irving Tucker, a citizen of the United States and a resident of the city of White Plains, in the county of Westchester and State of New York, have invented a new, original, and ornamental Design for a Baby Rattle, of which the following is a specification, reference being had to the accompanying drawing, forming part thereof.

Figure 1 is the front elevation view of the baby rattle, showing my new design.

Figure 2 is a side view thereof.

The opposite face of the baby rattle is identical with that disclosed.

I claim:

The ornamental design for a baby rattle, as shown and described.

IRVING TUCKER.
